UNITED STATES PATENT OFFICE.

WALTER V. TURNER, OF EDGEWOOD, PENNSYLVANIA, ASSIGNOR TO THE WESTINGHOUSE AIR BRAKE COMPANY, OF PITTSBURGH, PENNSYLVANIA, A CORPORATION OF PENNSYLVANIA.

TRIPLE-VALVE DEVICE.

1,073,186.

Specification of Letters Patent. Patented Sept. 16, 1913.

Application filed January 19, 1911. Serial No. 603,560.

To all whom it may concern:

Be it known that I, WALTER V. TURNER, a citizen of the United States, residing at Edgewood, in the county of Allegheny and State of Pennsylvania, have invented new and useful Improvements in Triple-Valve Devices, of which the following is a specification.

This invention relates to automatic fluid pressure brakes, and has for its object to provide improved means for securing a local venting of fluid from the train pipe in service applications of the brakes to thereby accelerate the movement of the successive triple valves throughout the train.

In the accompanying drawing, Figure 1 is a central sectional view of a triple valve device embodying my invention, showing the parts in normal full release position and Fig. 2 a similar view, with the parts shown in service application position.

The triple valve device illustrated in the drawing is of the so called retarded release type for securing a more uniform release of the brakes, particularly on long trains, but I wish it understood that my present improvement may be applied to various other types of triple valves.

As shown in the drawings, the triple valve device may comprise a casing 1 having a piston chamber 2 connected by passage 3 to the train pipe and containing triple valve piston 4, and having a valve chamber 5 open to the auxiliary reservoir and containing main slide valve 6 and auxiliary slide valve 7 mounted on the main slide valve and having a movement relative thereto.

A yielding resistance device 8 serves as a stop for the piston 4 to determine the normal full release position of the valves and is adapted to yieldingly resist movement of said valves to an inner retarded release position in which the exhaust from the brake cylinder is restricted.

In the present construction, the emergency quick action mechanism is utilized to control the quick service venting of air from the train pipe and comprises a movable abutment 9 contained in chamber 10 and provided with a stem 11 which extends through an opening in a partition wall 12 of the casing 1. Within a chamber 13 is contained a check valve 14 controlling communication from train pipe passage 3 to

said chamber and an emergency valve 15 adapted to control communication from chamber 13 to a passage 16 leading to the brake cylinder. The valve 15 is provided with a projecting portion 17 adapted to be engaged by the stem 11 of piston 9, said valve being normally maintained seated by a spring 18.

In addition to the graduating slide valve 7, an auxiliary puppet valve 19 is provided in the main slide valve 6 and this valve is operated by the movement of triple valve piston 4 in service applications to open communication from the auxiliary reservoir to a port 20 in the main slide valve, which port is adapted to register with a passage 21 leading to one side of the movable abutment 9.

The body of emergency valve 15 has a chamber containing a puppet valve 22 having a stem 23 adapted to project out through the portion 17, said valve being normally seated by a spring 24.

The train pipe being charged to the standard pressure in the usual manner, if it is desired to effect a service application of the brakes, a gradual reduction in train pipe pressure is made and the triple valve piston 4 is then moved outwardly. The first movement of said piston shifts the auxiliary slide valve 7 to uncover service port 25 in the main slide valve and port 20. The main slide valve 6 is then actuated to cause the service port 25 to register with port 26 leading to the brake cylinder passage 27 and port 20 to register with passage 21.

Fluid from the auxiliary reservoir then flows from the auxiliary reservoir to the brake cylinder through port 25 and fluid also flows through passage 21 to the outer face of the movable abutment 9. The abutment 9 is thereupon operated and the stem 11 engages the stem 23 and opens the valve 22 to thereby permit air to flow from the train pipe past check valve 14 to chamber 13 and thence through a restricted port 28 to passage 16 and the brake cylinder. A passage 29 leading to passage 16 is uncovered by the outward movement of piston 9 so that in the position shown in Fig. 2, the air flowing from the auxiliary reservoir through passage 21 flows through the passage 29 to the brake cylinder. The pressure on the outer face of said abutment is

thus relieved and prevents any further outward movement of the abutment to open the emergency valve 15.

As soon as the auxiliary reservoir pressure becomes reduced by flow to the brake cylinder to a point slightly less than the train pipe pressure, the triple valve piston moves inwardly and operates the auxiliary valves 7 and 19 to close the ports 25 and 20 respectively and the pressures then equalizing on opposite sides of the abutment 9, the same is shifted by the spring 30 to its normal position, permitting the valve 22 to close and prevent further venting of air from the train pipe. By making further gradual reductions in train pipe pressure, the auxiliary valves 7 and 19 may be again opened to supply air to the brake cylinder and also supply air to operate the abutment 9 and valve 22 to vent air from the train pipe in accordance with the operation hereinbefore described.

In an emergency application, the piston 4 moves out its full traverse and uncovers the usual large emergency port 31, which supplies air to the abutment 9 in such volume as to cause same to move outwardly with full force and thereby lift the emergency valve 15 from its seat, to produce the usual emergency venting of air from the train pipe.

Having now described my invention, what I claim as new and desire to secure by Letters Patent, is:—

1. A triple valve device for fluid pressure brakes, comprising a piston, a main slide valve operated thereby and having a graduating port adapted to communicate with a brake cylinder port in service application position, an auxiliary valve movable with the piston for controlling said graduating port, and a second auxiliary valve operated by said piston and adapted in service application position to effect the opening of a local train pipe discharge port.

2. A triple valve device for fluid pressure brakes, comprising a piston, a main slide valve operated thereby, a graduating slide valve mounted on said main slide valve and operated by the piston for controlling a brake cylinder service port, and an auxiliary puppet valve operated by said piston and adapted in service application position to effect the opening of a local train pipe discharge port.

3. A triple valve device for fluid pressure brakes, comprising a piston, a main slide valve operated thereby, a graduating slide valve mounted on said main slide valve and operated by the piston for controlling a brake cylinder service port, and an auxiliary valve mounted in the main slide valve and operated by said piston for effecting the opening of a local train pipe discharge port.

4. A triple valve device for fluid pressure

brakes, comprising a piston, a main slide valve operated thereby, a graduating slide valve mounted on said main slide valve and operated by the piston for controlling a brake cylinder service port, means for controlling a local train pipe discharge port, and an auxiliary valve carried by the main slide valve and operated in a service application of the brakes by said piston for supplying air to actuate said means.

5. A triple valve device for fluid pressure brakes, comprising a piston, a main slide valve operated thereby and having a brake cylinder service port adapted in service application position to register with a brake cylinder port, a graduating slide valve for controlling said service port, means operated by flow of air from the auxiliary reservoir to the brake cylinder for controlling a local train pipe discharge port, and an auxiliary valve carried by the main slide valve and operated by said piston in a service application of the brakes for supplying air from the auxiliary reservoir to operate said means.

6. A triple valve device for fluid pressure brakes, comprising a piston, a main slide valve operated thereby and having a brake cylinder service port adapted in service application position to register with a brake cylinder port, a graduating slide valve for controlling said service port, a valve for controlling a local train pipe discharge port, a movable abutment operated by flow of air from the auxiliary reservoir to the brake cylinder for actuating said valve, and an auxiliary valve mounted in the main slide valve and operated by said piston in a service application of the brakes to supply fluid from the auxiliary reservoir to said abutment to thereby open said valve and vent fluid from the train pipe.

7. A triple valve device, comprising a piston, a main slide valve operated thereby and having a service port adapted in service application position to register with a brake cylinder port for supplying air from the auxiliary reservoir to the brake cylinder, an auxiliary valve operated by said piston and having a movement relative to the main valve for controlling said service port, and a second auxiliary valve carried by said main valve and having a movement relative to the main valve and operated by said piston for effecting the opening of a local train pipe discharge port in a service application of the brakes.

8. A triple valve device, comprising a piston, a main slide valve operated thereby and having a service port adapted in service application position to register with a brake cylinder port for supplying air from the auxiliary reservoir to the brake cylinder, an auxiliary valve operated by said piston and having a movement relative to the main

valve for controlling said service port, an emergency valve for venting the train pipe in an emergency application of the brakes, a valve carried by said emergency valve for 5 locally venting the train pipe in a service application of the brakes, a movable abutment operated by flow of air from the auxiliary reservoir to the brake cylinder for opening said service train pipe vent valve, 10 and a second auxiliary valve operated by

said piston in a service application of the brakes for supplying air to actuate said movable abutment.

In testimony whereof I have hereunto set my hand.

WALTER V. TURNER.
